UNITED STATES PATENT OFFICE.

FRANK H. BLACKMARR, OF CHICAGO, ILLINOIS.

DESIGN FOR A DRINKING-FOUNTAIN.

46,797.

Specification for Design.

Patented Dec. 29, 1914.

Application filed October 3, 1914. Serial No. 864,957. Term of patent 14 years.

To all whom it may concern:

Be it known that I, FRANK H. BLACKMARR, a citizen of the United States, residing at Chicago, in the county of Cook and State of Illinois, have invented a new, original, and ornamental Design for Drinking-Fountains, of which the following is a specification, reference being had to the accompanying drawing, forming a part thereof.

The figure is a perspective elevation view of a drinking fountain, showing my new design.

I claim:

The ornamental design for a drinking fountain, as shown.

FRANK H. BLACKMARR.

Witnesses:

SAMUEL N. POND,

A. G. LATIMER.
